UNITED STATES PATENT OFFICE.

ARTHUR S. COWAN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FRICITION-PULLEY MECHANISM FOR LOOMS.

SPECIFICATION forming part of Letters Patent No. 690,016, dated December 31, 1901.

Application filed June 22, 1901. Serial No. 65,575. (No model.)

To all whom it may concern:

Be known that I, ARTHUR S. COWAN, a citizen of the United States, residing at Worcester, in the county of Worcester and State of 5 Massachusetts, have invented certain new and useful Improvements in Friction-Pulley Mechanism for Looms, of which the following is a specification.

My invention relates to friction-pulley 10 mechanism for driving-pulleys; and the object of my invention is to improve upon the ordinary construction of friction-pulley mechanisms for driving-pulleys, and more particularly to provide means for drawing the 15 loose driving or belt pulley against the friction-surface and locking it in its position when in contact with the friction-surface. It has been customary heretofore to move the loose driving or belt pulley against the friction-surface attached to the driving-shaft by 20 leverage, and considerable leverage is required to maintain a sufficient amount of friction between the pulley and the friction-surface to drive the shaft. This leverage is communicated to the shaft and causes friction in 25 the bearings of the shaft, and consequently waste of power, and also an end thrust to the shaft.

In my improvements the drawing of the 30 loose pulley toward the friction-surface and locking it thereto overcomes all tendencies of end thrust on the shaft.

My invention consists in certain novel features of construction of my friction-pulley 35 mechanism for loose driving or belt pulleys, as will be hereinafter fully described.

Referring to the drawings, Figure 1 is an end view of a loom-frame, showing my improvements in friction-pulley mechanism for 40 driving-pulleys applied thereto. Fig. 2 is a plan view of the parts shown in Fig. 1 looking in the direction of arrow *a*, same figure. Fig. 3 is, on an enlarged scale, a section on line 3-3, Fig. 1, looking in the direction of 45 arrow *b*, same figure, showing the driving-pulley out of engagement with the friction-disk; and Fig. 4 corresponds to Fig. 3, but shows the driving-pulley in engagement with and locked to the friction-surface.

50 In the accompanying drawings, 1 is the

loom side or frame. 2 is a shaft mounted in bearings on the loom-frame and on an arm 1', secured to the bracket 1", bolted to the frame 1, (see Fig. 2,) and having the driving or belt pulley 3 loose thereon. 4 is a driving-gear 55 secured on the shaft 2, in this instance by a spline 2'. The friction-surface is in this instance made in the shape of a circular plate or disk 5, provided with a hand-wheel 5', and having the arms 5" secured by bolts 6 and 60 nuts 7 to the gear 4, and with a friction-surface consisting of a ring of leather or other material 5", secured on the face of the disk 5, adjacent to the driving-pulley 3, which is loose on the shaft 2 and adapted to be moved 65 thereon in the direction of the length of the shaft and driven by a belt. (Not shown.) A friction-band wheel 9 (see Fig. 2) is secured to the gear 4, and around said wheel passes a friction-band, (not shown,) which is brought 70 into engagement with the wheel 9 when the shipper is thrown off in the ordinary way.

The parts above described correspond to similar parts ordinarily used in friction-pulley mechanism of looms.

I will now describe my improvements for moving and locking the driving-pulley 3.

On a collar 10, loosely mounted on the turned-down hub 3' of the pulley 3 and having an annular groove 10' therein, are two 80 oppositely-extending lugs or ears 10", to each of which is pivotally connected by a pin or stud 11 one end of a connector 12, forked at each end. The opposite forked end of each connector 12 is pivotally connected by a stud 85 13 with the head 14 of a bolt 15. Each bolt 15 is screwed into the outer end of a curved rocking lever 16, which is pivoted at its inner end on a stud 19, supported between two arms 17, extending out from a plate 18, secured to 90 the pulley 3, as by bolts 18'. (See Fig. 1.) A stud 20 pivotally secures the forked end of each rocking lever 16 to one end of a sliding bar 21, which extends in the forked end of the lever 16 and has its bearings in an opening in the pulley 3. The opposite end of each 95 sliding bar 21 has an open end slot 21' to extend over and receive an inwardly-projecting annular flange 5''' on the friction-disk 5. It will be noted that the end of the sliding 100

bar 21 by virtue of the slot 21' receives the annular flange 5''' of the friction-disk 5, so that sliding movement of the bar 21 in either direction positively moves the friction-disk 5 or pulley either into or out of engagement with each other by the walls of the slotted ends of the sliding bars engaging opposite sides of the flange and also that the flange of the friction-disk remains at all times in engagement with the slot 21' of the sliding bar 21, thus insuring positive action of the friction-disk upon any movement of the sliding bars. Within the open end slot 21' of each sliding bar 21 is preferably secured a piece 15 of fiber or other material 22.

I will now describe the shipping mechanism shown in the drawings and used in this instance to move the driving-pulley 3 on the shaft 2 into and out of engagement with the 20 friction-surface 5''' on the friction plate or disk.

The shipper-lever 23 is mounted on a stud 24 on the loom-frame 1 and has at its lower end a pin 23', which engages a slot 25' in the 25 rocker-arm 25, pivoted on a stud 26 in the loom-frame. The lower end of the rocker-arm 25 is connected by a link 27 with one arm of an angle-lever 28, having a hub 28' mounted on a stud 29 in a bracket 30, bolted to the loom- 30 frame. The other arm of the angle-lever 28 is attached to an adjustable connector 31, which is attached to the end of the lever 32, centrally pivoted at 33 in the slotted end 34' of the bolt 34, secured to the arm 1'. The 35 other end of the lever 33 is forked and has open end slots in its forked end to receive the pins 35', extending out from a ring 35, extending loosely in the annular groove 10' in the collar 10.

40 The operation of the locking mechanism for moving the pulley 3 into contact with the friction-surface 5''' on the friction-disk 5 and locking it thereto will be readily understood by referring to Figs. 3 and 4.

45 When the shipper-lever 23 is in the position shown in Fig. 1, the driving-pulley 3 is in contact with the friction-surface 5''' on the friction-disk 5, as shown in Figs. 2 and 4, and the shaft 2 and the gear 4 are operated.

50 When the shipper-lever 23 is moved in the direction of arrow c, Fig. 1, the pulley 3, through intermediate connections, is moved out of engagement with the friction-surface 5''' on the friction-disk 5 and into the position shown 55 in Fig. 3, allowing the pulley 3 to run loose on the shaft 2. The drawing forward of the shipper-lever 23 to move the pulley 3 into contact with the friction-surface 5''' will, through rocker-arm 25, link 27, angle-lever 60 28, connector 31, and lever 32, move the collar 10 in the direction of arrow d, Fig. 3, and cause the rocking levers 16, through connectors 12 and bolts 15, to be moved on their pivotal supports and move the sliding bars 21 to 65 cause them to engage the annular flange 5''' on the friction-disk 5 and move the driving-pulley 3 on the shaft 2 into engagement with

the friction-surface 5''' on said friction-disk 5, as shown in Fig. 3. The movement of the collar 10, above described, brings the studs 11 70 into alignment with the studs 13 and holds the rocking levers 16 and sliding bars 21 to lock the pulley 3 to the friction-disk. When the shipper-lever 23 is moved into the opposite direction, the collar 10, through intermediate connections, is moved in the direction of arrow e, Fig. 4, into the position shown in Fig. 3, and if the pulley 3 and friction-surface 5''' do not disengage readily the lip 21'' 80 on the sliding plate 21 coming into contact with the flange 5''' on the friction-disk 5 will force the pulley 3 away from the friction-disk 5.

It will be understood that the details of construction of my improvements may be varied, 85 if desired. Any other well-known construction of shipping mechanism to move the collar 10 may be employed, if desired.

It is not necessary that the friction plate or surface be attached to the gear 4. It may be 90 made separate therefrom and both fast on the shaft. Instead of a rotating shaft a stationary shaft or journal may be used, the friction-plate 5 and gear 4 being loose thereon and the gear 4 meshing into and driving another 95 gear on another shaft, if desired.

Having thus described my invention, what I claim as new, and desire to secure by Letters Patent, is—

1. In a friction-pulley mechanism, the combination of a shaft, a friction disk or plate, and a pulley, one of said parts being fast and the other loose on said shaft, and means for positively moving said friction disk or plate and said pulley into and out of frictional engagement, said means comprising bearings in said pulley, sliding bars moving lengthwise in said bearings and having slotted ends, a flange on said friction disk or plate in engagement with the slotted ends of said sliding bars whereby the walls of said slots engage opposite sides of the said flange to move the parts positively into and out of engagement, a sliding collar on the shaft and means intermediate said collar and sliding bars for moving the latter from the former.

2. In a friction-pulley mechanism, the combination of a shaft, a friction disk or plate fast on said shaft, a pulley loose on said shaft and provided with bearings, sliding bars movable in said bearing in the loose pulley, rocking levers pivoted on said loose pulley and connected to said sliding bars, a collar loose on the shaft and means intermediate the collar and rocking levers for moving the sliding bars, the said friction-disk being provided with a flange, and said sliding bars having slotted ends engaged by said flange, the walls of said slotted ends adapted to engage opposite sides of said flange to positively move the loose pulley into and out of engagement with the friction-disk.

3. In a friction-pulley mechanism, the combination of a shaft, a friction disk or plate,

and a pulley, one of said parts being fast and the other loose on said shaft, and means for positively moving said friction disk or plate and said pulley into and out of frictional engagement, said means comprising bearings in said pulley, sliding bars movable lengthwise in said bearings and having slotted ends, a flange on said friction disk or plate in engagement with the slotted ends of said sliding bars whereby the walls of said slots engage opposite sides of the said flange to move the parts positively into or out of engagement, a sliding collar on the shaft, rocking levers pivoted on said pulley, connections between said rocking levers and the sliding bars, and connectors joining the rocking levers and the sliding collar.

4. In a friction-pulley mechanism, the combination of a shaft, a gear fast on said shaft, a friction disk or plate secured to said gear, a pulley loose on said shaft and adapted to be moved into engagement with the friction-disk, bearings in said pulley, sliding bars movable in said bearings and provided with slotted ends, said friction disk or plate being provided with a flange in engagement with the slotted ends of the sliding bars, the walls of the said slotted ends adapted to engage the opposite sides of said flange to cause a positive movement of the pulley into and out of

engagement with said friction-disk, rocking levers carried by said pulley and connected to the sliding bars, and means for operating the rocking levers to move the sliding bars in their bearings in the pulley.

5. In a friction-pulley mechanism, the combination of a shaft, a gear fast on said shaft, a friction disk or plate secured to said gear, a pulley loose on said shaft and adapted to be moved into engagement with the friction-disk, bearings in said pulley, sliding bars movable in said bearings and provided with slotted ends, said friction disk or plate being provided with a flange in engagement with the slotted ends of the sliding bars, the walls of the said slotted ends adapted to engage the opposite sides of said flange to cause a positive movement of the pulley into and out of engagement with said friction-disk, rocking levers carried by said pulley and connected to the sliding bars, bolts adjustably engaging the ends of the rocking levers, a collar loose on the said shaft, and connectors joining the collar and bolts to move the sliding bars in their bearings in the pulley.
